UNITED STATES PATENT OFFICE.

HENRY W. O'DOWD, OF JERSEY CITY, NEW JERSEY, ASSIGNOR TO WILLIAM M. CRANE COMPANY, A CORPORATION OF NEW YORK.

GAS RANGE.

Application filed August 24, 1921. Serial No. 495,077.

To all whom it may concern:

Be it known that I, HENRY W. O'Dowd, a citizen of the United States, residing at Jersey City, in the county of Hudson and State of New Jersey, have invented certain new and useful Improvements in Gas Ranges, of which the following is a specification, reference being had therein to the accompanying drawings.

This invention, while applicable to heating apparatus in general, relates more particularly to gas or like ranges of the kind having a closed top adapted to be heated by the burner of an underlying combustion chamber.

The primary object of the present invention is to improve the efficiency of gas ranges of this kind, and the invention is directed to certain improvements in the various parts having that general object in view. These improvements will best be understood from the detailed description to follow:

In the drawings:

Fig. 1 is a top plan view, partly broken away, of a gas range equipped with the improvements;

Fig. 2 is a vertical section taken on the line A—A of Fig. 1;

Fig. 3 is a vertical section taken on the line B—B of Fig. 1;

Fig. 4 is a vertical section taken on the line C—C of Fig. 1;

Fig. 5 is a plan view, partly broken away, of the burner arrangement;

Fig. 6 is a perspective view of the manifold and its supporting bracket, showing the parts in unassembled condition;

Fig. 7 is a top plan view, partly broken away, of the range as equipped with a modified form of burner; and

Fig. 8 is a vertical section taken on the line D—D of Fig. 7.

The body of the range, denoted as a whole by the reference numeral 1, may be of any suitable shape or design, but it is preferably made square or rectangular as shown. The upper part of the range is devoted to a combustion chamber 2 having a closed cooking top 3, a bottom plate 4, and surrounding walls or partitions 5, these parts thus enclosing the combustion chamber on all sides. The top 3 is made in sections and is pro-

vided with the customary removable lids, as shown. The chamber walls 5, it will be observed, are spaced inwardly from the outer walls 6 of the range, the two walls thus providing, in conjunction with the top and bottom plates 3 and 4, a flue 7 entirely surrounding or circumscribing the combustion chamber. Near the top, the walls 5 are each formed with a series of holes or apertures 8 which establish communication between the combustion chamber 2 and the flue 7 at various points around the chamber. At the rear, the range wall 6 is formed with an exit 9 leading into a pocket 10 of an outlet or chimney 11. By means of this arrangement, there will be produced in the range a natural draft which tends to pull the heated products of combustion from the combustion chamber 2 through the holes 8 into the surrounding flue 7 and thence around the flue to the exit 9, where they escape through the chimney 11 at the rear. As the openings 8 are formed in all four walls of the combustion chamber, the heat currents are necessarily distributed in all directions and hence are caused to heat the closed top 3 throughout its entire surface. As the products of combustion pass through the flue, more heat is naturally imparted to the closed top, which is thus heated to its outermost margin. The area of the holes 8 is so regulated that the products of combustion, although sufficiently delayed in their escape to afford enough time for the absorption of the heat units, will be allowed to expand in the desired manner without creating any objectionable back pressure.

In Figs. 1 to 5, the Bunsen burner for the combustion chamber is made up of a series of concentric rings 12, each formed with a series of nibs 13 having orifices through which the gas issues. Extending forwardly from the respective burner rings are mixing tubes 14 provided with the customary primary air chambers 15 disposed in a row at the front of the range. In order to make room for the burner tubes 14, the front walls 5 and 6 of the flue 7 are recessed as at 16, it being noted that the flue is closed around the recess. It may also be noted that the flue is provided at this point with a peep hole 17 containing a screen of wire gauze or

the like. A plate 18 fitted over the burner tubes serves as a closure for the recess 16. The burner rings 12 are completely enclosed within a box or housing comprising an upper part 19 and a lower part 20, the two parts as shown being tightly fitted together about the burner rings and their mixing tubes 14 and separable at will to give access to the burner for cleaning or removal. 10 The lower part of the housing is formed with air inlet openings 21 which may be of any desired form or arrangement so long as they are capable of furnishing the necessary supply of secondary air to the burner. The 15 upper part of the housing is formed with air discharge nozzles 22 arranged in vertical alignment with the burner orifices and consequently disposed in concentric rows or series to correspond. As best shown in Fig. 4, the gas nibs 13 of the burner rings 12 project into and are centered within tapered bores or openings of the discharge nozzles 22, the idea being to provide for the entrainment of secondary air at the flame ports, as 20 will be more fully explained at a later point. The burner rings are supported within the housing upon lugs or projections 23 standing up from the bottom of the part 20 and which maintain said rings at the proper 25 elevation within the housing. The housing itself is located in a recess formed in the bottom plate 4 of the combustion chamber and is supported upon an underlying plate 24, from which the housing is spaced by legs 30 25. The slight depression formed in the plate 24 is merely intended to locate the housing at the proper distance from the closed top 3. The plate 24 extends from one side of the range to the other and has its 35 front and rear edges turned upwardly to meet the plate 4, the two plates thus providing between them a secondary air passage 40 26 leading to the burner and communicating with the atmosphere through holes or 45 openings 27 formed in the side walls 6 of the range. It may be noted that the housing is provided on its lower part with a peripheral flange 28 resting upon the bottom plate 4 of the combustion chamber and shutting off 50 communication between said chamber and the secondary air passage 26 around the housing. The secondary air, in entering the combustion chamber, is thus obliged to follow the path generally indicated by the 55 arrows in Fig. 4. It will be seen that no secondary air is allowed to enter the combustion chamber without passing the burner, which is an important factor in obtaining the proper flame propagation. This particular effect would be secured by the use of the lower part 20 of the housing alone, but by employing the upper part 19 as well, the air is prevented from entering the combustion chamber except through the discharge 60 nozzles 22, which thereby enable the flame

jets to entrain the exact quantity of secondary air required for perfect combustion. The housing therefore provides in effect a secondary air chamber which is completely separated from the combustion chamber except at the points where the gas is ignited. Although desirable, it is not essential that the burner be completely enclosed within such secondary air chamber, as the more important thing is to cause the secondary air to enter the combustion chamber solely by way of the discharge nozzles. 70

Many advantages characterize the foregoing construction: For instance, the secondary air is supplied to the burner in its pure atmospheric condition, being prevented from mixing with the products of combustion before it reaches the flame ports. Again, the burner, being protected against the heat of the products of combustion, has less tendency to cause an excessive expansion of the contained gas such as would reduce the entrainment of the primary air. On the other hand, the air pocketed within the housing becomes heated by the products of combustion and may therefore be more effectively entrained at the flame ports. In this connection, it may be stated that the tapered bores of the discharge nozzles 22 not only facilitate the proper entrainment 85 of secondary air, but also serve to effect a thorough admixture of the gas and air in promoting combustion. It is also pointed out that, due to the restricted openings of the discharge nozzles, the pressure of the products of combustion at the burner orifices is reduced to a minimum, thereby lessening the tendency to back pressure and hence more nearly preserving the initial entrainment of primary air. Actual practice 90 has shown that, in the use of a burner arrangement as above described, the initial combustion may be maintained almost indefinitely. 100

Located within the combustion chamber 2 is a bed or layer of refractory material 29, such as fire brick, capable of absorbing heat and transmitting it by radiation. In the present instance, the material is supported upon the bottom plate 4 of the combustion chamber and substantially fills the entire space between the two-part housing 19, 20, and the flue 7. The material thus presents an extensive surface to the heated products of combustion, and hence is capable of abstracting a considerable amount of additional heat therefrom before they finally escape from the range. Such abstraction of heat, of course, is greatly facilitated by the flue arrangement, previously described, which it will be remembered acts to delay the escape of the products from the range. It is apparent, therefore, that this fire brick material by its heat radiation, aids appreciably in heating the closed top and in im- 110 115 120 125 130

proving the heating capacity of the range in general.

The gas is supplied to the burner 12 through a pipe or manifold 30 provided as usual with stop cocks 31 and gas nozzles 32, these latter projecting into the primary air chambers 15 before referred to. It is essential that the nozzles 32 be centered in relation to the air chambers 15, as otherwise the proper entrainment of primary air will be seriously interfered with. While the various parts are generally made with great accuracy to meet this requirement, nevertheless it frequently happens that the manifold 15 is disarranged in shipment or in fitting it to the main pipe connections. To obviate this defect, locking means are herein provided to locate and hold the manifold in a definite and fixed position so as to maintain the gas nozzles in proper centered relation to the primary air chambers at all times. In the present instance, the desired result is accomplished by providing the manifold 30 at its opposite ends with hexagonal or non-cylindrical bosses 33 fitted into correspondingly shaped sockets 34 of supporting brackets 35, the latter having front detachable sections 36 to permit the ready removal or application of the manifold. The manifold is also provided at its opposite ends with laterally projecting studs 37 arranged to engage the inner faces of the supporting brackets 35. By this simple arrangement, the manifold is positively locked against displacement in any direction, and in particular against turning or axial shifting, thereby rendering it impossible in fitting or shipment to disturb the proper relation of the parts. This particular arrangement is merely intended as an example of a suitable locking means, and it will now be obvious that the manifold and its supporting brackets could be relatively formed in some other way to locate and maintain the manifold in the required position.

The range illustrated in Figs. 7 and 8 is substantially the same as that above described except as to the burner equipment. In this instance, the burner simply comprises a single tube 38 extending entirely across the combustion chamber from front to rear and provided at the front with a single air chamber 38^a. The manifold 30 is consequently provided with but one gas nozzle 32. The burner tube 38, like the burner rings 12, is provided with a series of gas nibs 39 projecting into the tapered bores of air discharge nozzles 40 formed in the upper wall of an oblong housing 41, which latter is formed in its lower wall with inlet openings 42 to admit secondary air to the housing from the passage 26. This housing, like the other, is supported upon the plate 24, having legs 43 to maintain it at the proper height. The function of the

housing is precisely the same as before described, so that no further explanation seems necessary. In view of the long and narrow form of the housing 41, the fire brick material 29 laid between it and the flue 7 will necessarily present more surface to the heated products of combustion.

In both embodiments above discussed, the range is provided beneath the combustion chamber 2 with an oven 44, whose upper wall 45 is formed with holes or openings 46 leading into a horizontal flue 47 having an exit 48 discharging into the chimney pocket 10 before referred to. The plate 24 of course shuts off any communication between the flue 47 and the secondary air passage 26.

The invention is not of course confined to the precise constructions shown and described, nor to any other particular construction by which the same may be carried into effect, as many changes may be made in the details without departing from the main principles of the invention and without sacrificing its chief advantages. It should be understood, therefore, that the invention is not limited to any specific form or embodiment except in so far as such limitations are set forth in the appended claims. It should also be understood that, while the several features set forth mutually cooperate in a peculiar way in attaining the general object stated, they might be used alone or in connection with other features as well. For instance, the improved burner arrangement or the improved manifold mounting could be applied to various other kinds of ranges or heating apparatus to very good advantage.

Having thus described my invention, what I claim is:

1. A gas-range including, in combination, a combustion chamber, a closed top therefor, a flue surrounding said chamber and communicating therewith, a Bunsen burner, and a member formed with secondary air discharge openings leading into the combustion chamber and through which the burner flames project, the said member being constructed to exclude secondary air from the combustion chamber except through said discharge openings.

2. A gas-range including, in combination, a combustion chamber, a closed top therefor, a flue surrounding said chamber and communicating therewith, a secondary air chamber separated from the combustion chamber and having air discharge openings leading thereto, and a burner located within the secondary air chamber and having its gas orifices arranged to project the flame jets through said air discharge openings.

3. A gas-range including, in combination, a combustion chamber, a closed top therefor, a flue surrounding said chamber and communicating therewith, a burner, and a hous-

105

- ing completely enclosing the burner and its gas orifices arranged in centered relation to said secondary air discharge nozzles.
5. A gas-range including, in combination, a combustion chamber, a closed top therefor, a passage for secondary air extending beneath the combustion chamber, a flue 10 surrounding said chamber and communicating therewith, a burner, and a housing completely enclosing the burner and formed with air inlet and outlet openings, the air inlet openings leading from the secondary air passage, and the air outlet openings leading into the combustion chamber and arranged in alignment with the burner orifices.
10. In a heating apparatus, the combination of a combustion chamber, a secondary air chamber separated therefrom and having air discharge nozzles formed with tapered openings leading into the combustion chamber, and a Bunsen burner located within the secondary air chamber and formed with gas nibs projecting into the tapered 75 openings of said secondary air discharge nozzles.
11. A burner equipment for gas heating apparatus comprising a Bunsen burner formed with gas orifices, and a housing completely enclosing the burner and formed with inlet and outlet openings for secondary air, the said outlet openings being arranged in alignment with the gas orifices, for the purpose described.
12. A burner equipment for gas heating apparatus comprising a Bunsen burner formed with gas orifices, and a housing completely enclosing the burner and formed with inlet and outlet openings for secondary air, the said outlet openings being tapered 90 and arranged in centered relation to the gas orifices.
13. A burner equipment for gas heating apparatus comprising a Bunsen burner formed with gas nibs, and a housing completely enclosing the burner and formed with inlet openings and discharge nozzles for secondary air, the said nozzles having tapered openings and arranged with the gas nibs projecting into said openings.
14. A burner equipment for gas heating apparatus comprising a Bunsen burner formed with gas orifices, and a housing completely enclosing the burner and formed with inlet and outlet openings for secondary air, the latter arranged in alignment with the gas orifices, and the said housing being formed in separable sections to permit the burner to be inserted in or removed from 105 the housing, as required.
15. In a heating apparatus, the combination of a combustion chamber, a Bunsen burner having a series of gas orifices, and a member formed with secondary air discharge 115 openings surrounding the gas orifices, the said discharge openings constituting the sole means for admitting secondary air into the combustion chamber and acting to discharge said secondary air in individual streams directly at the respective gas orifices for immediate contact with the flame jets.
16. A gas range including, in combination, a combustion chamber, a closed top therefor, a Bunsen burner located in said 125 chamber, and a member overlying the burner and formed with secondary air discharge openings through which the burner flames project, the said member being constructed to exclude secondary air from the combus- 130
17. A gas-range including, in combination, a combustion chamber, a closed top therefor, a burner, and a housing completely enclosing the burner and formed with air inlet and outlet openings, the air inlet openings leading from the secondary air passage, and the air outlet openings leading into the combustion chamber and arranged in alignment with the burner orifices.
18. A gas-range including, in combination, a combustion chamber, a closed top therefor, a passage for secondary air extending beneath the combustion chamber, a flue 10 surrounding said chamber and communicating therewith, a burner, and a housing completely enclosing the burner and formed with air inlet and outlet openings, the air inlet openings leading from the secondary air passage, and the air outlet openings leading into the combustion chamber and arranged in alignment with the burner orifices.
19. A gas-range including, in combination, a combustion chamber, a closed top therefor, a flue surrounding said chamber and communicating therewith, a burner, a housing completely enclosing the burner and formed with secondary air inlet and outlet openings, the latter leading into the combustion chamber and arranged in alignment with the burner orifices, and a bed of refractory material located within the combustion chamber and filling the space between the burner housing and the flue.
20. In a heating apparatus, the combination of a combustion chamber, a Bunsen burner formed with gas orifices, and a member formed with secondary air discharge openings leading into the combustion chamber and through which the flame jets project, the said discharge openings constituting the sole means for admitting secondary air into the combustion chamber.
25. In a heating apparatus, the combination of a combustion chamber, a Bunsen burner formed with gas nibs, and a member formed with secondary air discharge nozzles having tapered openings leading into the combustion chamber and arranged with the gas nibs projecting into said tapered openings, the said member being constructed to exclude secondary air from the combustion chamber except through the discharge nozzles.
30. In a heating apparatus, the combination of a combustion chamber, a Bunsen burner formed with gas nibs, and a member formed with secondary air discharge nozzles having tapered openings leading into the combustion chamber and arranged with the gas nibs projecting into said tapered openings, the said member being constructed to exclude secondary air from the combustion chamber except through the discharge nozzles.
35. In a heating apparatus, the combination of a combustion chamber, a Bunsen burner formed with gas nibs, and a member formed with secondary air discharge nozzles having tapered openings leading into the combustion chamber and arranged with the gas nibs projecting into said tapered openings, the said member being constructed to exclude secondary air from the combustion chamber except through the discharge nozzles.
40. In a heating apparatus, the combination of a combustion chamber, a Bunsen burner formed with gas nibs, and a member formed with secondary air discharge nozzles having tapered openings leading into the combustion chamber and arranged with the gas nibs projecting into said tapered openings, the said member being constructed to exclude secondary air from the combustion chamber except through the discharge nozzles.
45. In a heating apparatus, the combination of a combustion chamber, a Bunsen burner formed with gas nibs, and a member formed with secondary air discharge nozzles having tapered openings leading into the combustion chamber and arranged with the gas nibs projecting into said tapered openings, the said member being constructed to exclude secondary air from the combustion chamber except through the discharge nozzles.
50. In a heating apparatus, the combination of a combustion chamber, a secondary air chamber separated therefrom and having air discharge openings leading thereinto, and a Bunsen burner located within the secondary air chamber and having its gas orifices arranged to project the flame jets through said secondary air discharge openings.
55. In a heating apparatus, the combination of a combustion chamber, a secondary air chamber separated therefrom and having air discharge nozzles formed with tapered openings leading into the combustion chamber, and a Bunsen burner located within the secondary air chamber and having

tion chamber except through said discharge openings.

17. A gas range including, in combination, a combustion chamber, a closed top ⁵ therefor, a secondary air chamber separated from the combustion chamber and having air discharge openings leading thereto,

and a Bunsen burner located within the secondary air chamber and having its gas orifices arranged to project the flame jets ¹⁰ through said air discharge openings.

In testimony whereof, I have affixed my signature hereto.

HENRY W. O'DOWD.
